UNITED STATES PATENT OFFICE.

MARIO ORIOLI AND CARLO BERTOLOTTI, OF NEW YORK, N. Y.

DESIGN FOR A HORSE-CAP.

41,745.

Specification for Design.

Patented Sept. 5, 1911.

Application filed December 8, 1910. Serial No. 596,379. Term of patent 14 years.

To all whom it may concern:

Be it known that we, MARIO ORIOLI and CARLO BERTOLOTTI, citizens of the United States, residing at New York city, in the county of New York, State of New York, have invented a certain new, original, and ornamental Design for Horse-Caps; and we do hereby declare the following to be a full, clear, and exact description of the design.

The figure is a perspective view showing the horse cap in position on a horse's head.

We claim:

The ornamental design for a horse cap, as shown.

MARIO ORIOLI.
CARLO BERTOLOTTI.
